CAR DOOR

Ferdinand H. Lange, Wilkes-Barre, Pa., assignor
of one-third to William L. Teeter, Kingston,
and one-third to R. B. Grontkowski, Hazleton,
Pa.

Application August 23, 1944, Serial No. 550,803

1 Claim. (Cl. 16—87)

1 The present invention appertains to new and useful improvements in freight car doors, the principal object of the invention being to provide a car door which can be moved easily and safely and which will have practically no tendency to bind under any circumstances.

Another important object of the invention is to provide a car door of the sliding type wherein, due to the provision of spring-supported rollers, the possibility of vibration and rattling is reduced to a minimum.

Other objects and advantages of the invention shall become apparent to the reader of the following description.

In the drawing:

Figure 1 is a fragmentary side elevational view of the door and a portion of a freight car, with the upper guide partly in section.

Figure 2 is a section taken substantially on line 2—2 of Figure 1.

Figure 3 is a section taken substantially on line 3—3 of Figure 1.

Referring to the drawing, wherein like numerals designate like parts, it can be seen that numeral 5 denotes a conventional freight car or the like. Numeral 6 generally refers to the improved door which is operative over a door opening 7 in the side of the car 5. More specifically, the door 6 includes improved upper and lower guides generally referred to by numerals 8 and 9.

The guide 9, as shown in Figure 3, consists of an elongated rail 10 supported by an outstanding shelf 11 projecting from an elongated attaching plate 12, this plate having openings therein for the reception of attaching bolts or the like 13. At frequent intervals, the shelf 11 has openings 14 therein for the purpose of drainage and so that any accumulation of foreign matter can be easily cleaned from the shelf.

The rail 10 is beveled upwardly on both of its sides to conform with the cross sectional shape of the grooved portions of rollers 15, each roller 15 having a groove, the side walls of which flare outwardly.

The rollers are mounted on axles 16 which bridge skirt plates 17, 17 depending from opposite sides of the lower edge of the door 6 and which are secured to the door 6 by rivets or bolts 18.

The upper guide structure 8 consists of a car attached elongated plate 19 having an outstanding flange portion 20 and this at its outer portion has a depending longitudinally extending skirt 21.

Secured by rivets or the like 22 to the under side of the flange 20 is a crank plate 23. A depending rib 24 extending longitudinally on the plate 23 serves as a track for upper rollers 25.

The upper rollers 25 are mounted within bifurcated end portions 26 of elongated strip spring

2 arms 27 which extend in opposite directions from a channeled member 28, this member being secured by rivets or bolts 29 to the intermediate portion of the upper part of the door 6. These spring arms 27 serve to hold the rollers 25 snugly against the track 24.

It will be observed that the track 24 is beveled downwardly on its opposite side to conform with the outwardly flaring side walls of the groove of each roller 25.

Obviously, there is positively no chance of the door jumping the guide structure and due to the provision of the spring arms 27 and the roller 25, there will be practically no likelihood of vibration or rattling of the door 6.

While the foregoing specifications sets forth the invention in specific terms, it is to be understood that numerous changes in the shape, size, and materials may be resorted to without departing from the spirit and scope of the invention as claimed hereinafter.

Having described the invention, what is claimed as new is:

25 A door assembly for railway rolling stock comprising a door panel, an elongated spring having at its intermediate portion a pair of parallel downwardly extending flanges bolted to the intermediate portion of the upper edge margin of the panel and having bifurcated ends, a roller journaled in and between the bifurcations of each spring end and having a peripheral groove tapering inwardly, a guiding track for the panel and including a horizontal portion overlying the upper edge of the panel and a vertical flange overlapping the upper margin of the front side of the door, a crank plate affixed at its upper side to the lower side of the horizontal portion of the track and having on its lower side a longitudinal rib of downwardly tapering transverse connection, said rib for engaging in the grooves of the rollers.

FERDINAND H. LANGE.
